UNITED STATES PATENT OFFICE.

DANIEL D. FRASER, OF BOSTON, MASSACHUSETTS.

ATTACHING DEVICE FOR WHIP-SOCKETS.

SPECIFICATION forming part of Letters Patent No. 403,260, dated May 14, 1889.

Application filed February 13, 1889. Serial No. 299,699. (No model.)

To all whom it may concern:

Be it known that I, DANIEL D. FRASER, a citizen of the United States, residing at Boston, in the county of Suffolk, State of Massachusetts, have invented certain new and useful Improvements in Attaching Devices for Whip-Sockets, of which the following is a specification, reference being had therein to the accompanying drawings.

10 This invention has relation to a whip-socket attaching device, the main object being the provision of a combined encircling ring and spring-tongue and clamping-bracket, which can be manufactured at a minimum cost, and 15 which will at the same time be neat and attractive.

Other objects and advantages of the invention will appear in the following description, and the novel features thereof will be particularly pointed out in the claims.

Referring to the drawings, Figure 1 is a longitudinal section of a whip-socket with an attaching device constructed in accordance with my invention. Fig. 2 is a side elevation 25 of the same. Fig. 3 is a perspective of the clamping device, hereinafter described. Fig. 4 is a perspective of the combined encircling ring and spring-arm; and Fig. 5 is a cross-section, on the line $x-x$ of Fig. 2, of a whip-30 socket provided with the device.

Like letters refer to like parts in all the figures of the drawings.

A represents an ordinary whip-socket of the usual construction. The interior of the 35 whip-socket is grooved, as at A', for the reception of the usual rubber ring or washer, B, which serves to retain the whip in a rigid and snug position. Near the bottom of the socket the bore is diminished, so that particles of 40 dirt and other refuse may find an exit.

Referring now more particularly to Fig. 4, C represents the encircling or binding ring, which terminates in the spring-arm C'. The ring C is made of metal, preferably resilient, 45 and is perforated, as at C² C³, for the reception of a binding-screw, D, which acts to bind the ring to snugly fit around the socket. C⁴ represents a perforation for the reception of a clamping-screw, D', the function of which 50 will be hereinafter described.

Referring to Fig. 3, E represents what I term a "clamp-bracket," which aids in binding the ring firmly around the socket and in connecting the socket with a dash. The clamp-bracket is offset, as at E', said offset being perforated, as at E², for the reception of the clamping-screw D'. It is also perforated, as at E⁴, for the reception of the binding-screw D. The wall of the clamping device opposite to the wall provided with the offset 55 is cut away to allow the ring to be drawn inwardly to bind upon the socket, leaving the cross-bar E³, the function of which is to serve as an abutment, against which the spring-arm C' is adapted to rest. The lower edges of the 60 clamping-bracket are cut away to conform to the shape of the socket.

To provide a socket with my attaching device, the ring C, having the perforation C³, is inserted within the clamping-bracket and the 70 body portion of the ring passed around the socket until it reaches the cross-bar E³, against which it abuts, as before stated. The spring-arm is then brought over to a desired position, and the binding-screw D is passed 75 through the perforations C², C³, and C⁴, and the ring and bracket are thereby firmly secured on the socket. It now remains to insert the clamping-screw D', which will adapt 80 the socket to fit the dash of any manner of vehicle.

To attach the socket to a dash, the clamping-screw D' is removed, and a slight puncture is made through the leather or other material of the dash, sufficient to admit said 85 screw, when the clamping-screw is placed in position and tightened. A ring and bracket is provided at each end of the socket.

From the above description it will be seen that an attaching device is provided which 90 consists of as few parts as possible, and which is strong, serviceable, and capable of being manufactured at a minimum cost.

Having described my invention, what I claim is—

1. In a whip-socket attaching device, the combination of an encircling band or ring terminating in an arm and perforated, as described, with a binding-bracket having at one end a solid wall and a projection, each per- 95 100

forated for the reception of a binding and clamping screw, respectively, and at the other end a cross-bar, substantially as specified.

2. In a whip-socket attaching device, the 5 clamp-bracket E, having the perforated projection E', the adjacent solid end perforated, as at E⁴, and the opposite open end provided with a cross-bar, E³, in combination with an encircling spring, substantially as specified.

In testimony whereof I affix my signature in 10 presence of two witnesses.

DANIEL D. FRASER.
